Inventor.

R. M. CURTICE

UNITED STATES PATENT OFFICE.

R. M. CURTICE, OF NORTH ADAMS, MICHIGAN.

CIDER-MILL.

Specification of Letters Patent No. 26,752, dated January 10, 1860.

To all whom it may concern:

Be it known that I, R. M. CURTICE, of North Adams, in the county of Hillsdale and State of Michigan, have invented a new and Improved Cider Mill and Press; and I do hereby declare that the following is a full, clear, and exact description of the same, reference being had to the annexed drawings, making a part of this specification, in which—

Figure 1 is a side sectional view of my invention, taken in the line x, x , Fig. 3. Fig. 2 is a side sectional view of ditto, taken in the line y, y , Fig. 3. Fig. 3 is a horizontal section of ditto, taken in the line z, z , Fig. 2.

Similar letters of reference indicate corresponding parts in the several figures.

This invention consists in combining with the ordinary fluted cylinders previously used for crushing apples, a spheroidal toothed cutter or grater, placed within a suitable hopper and arranged to operate substantially as hereinafter shown, whereby the crushing of the apples in the process of manufacturing cider is greatly expedited.

To enable those skilled in the art to fully understand and construct my invention I will proceed to describe it.

30 A represents a frame which may be constructed in any proper way to support the working parts of the machine.

B is a hopper which is placed on the upper part of the frame; and C is a spheroidal toothed cutter, which is placed on a proper shaft, D, the latter being fitted in suitable bearings on the frame. The cutter, C, may be of cast iron and either solid or in the form of a shell, according to the size of the machine. The shape of the cutter is plainly shown in Fig. 2. Within the hopper, B, an inclined board, a, is placed to guide the apples to the cutter, and the interior of the hopper at its lower end directly in front of the cutter by means of side pieces, a', a', is made to approximate in form to the convexity of the surface of the cutter, as shown clearly in Fig. 3.

Within the frame, A, directly below the cutter, C, two fluted cylinders, E E, are placed transversely. These fluted cylinders are made to gear into each other, and on one

end of the shaft, b, of one of the cylinders, a toothed wheel, F, is placed, said wheel gearing into a pinion, c, on the shaft, D, of 55 the cutter C. Into each cylinder, E, a clearer, G, works. These clearers are bars which are made of such dimensions that they may fit into the spaces between the projections on the cylinders. These bars extend the whole length of the cylinders and they are attached to springs, H, which have a tendency to keep the clearers in contact with the cylinders. To the side of the frame, A, opposite the wheel, F, a pawl, I, is attached, said pawls catching into wheel F. 60

On the frame, A, and by one end of the cylinders, E E, a rectangular box, J, is placed. Directly over this box a bar, K, is placed, said bar being fitted on two upright metal bars, L L, which are notched at one or both sides as shown at d, in Fig. 1. The lower ends of the bars L, L, are permanently attached to the frame, A, and said bars pass through mortises in the bar, K. 70 On the upper surface of the bar, K, two catches e, e, are secured. These catches are simply small metal bars connected at one end to the bar by pivots, g, and having each a spring, h, bearing against their opposite 75 ends, said springs having a tendency to keep the bars in the notches, d, of the bars, L L. On the bar, K, and near each bar, L, there is an upright ledge, i. These ledges form fulcrum bearings for levers, M, the inner 80 ends of which catch into the notches, d, of the bars, L L. By pressing down the outer ends of the levers, M, the bar, K, will be forced down and retained by the catches, e e.

By this arrangement a very simple and 90 efficient press is obtained for expressing the juice from the crushed apples. The apples are crushed as follows: Power is applied to the shaft, b, and the cutter, C, and cylinders, E E, rotate in the direction indicated 95 by the arrows. The cutter, C, reduces the apples to a fine state and greatly facilitates the crushing operation performed by the cylinders, E E, the cut apples falling from the hopper, B, between said cylinders. The 100 clearers, G G, effectually prevent the clogging or choking up of the cylinders, so that they will always operate efficiently. By having the cutter, C, of spheroidal form it

operates with less power than the cylindrical form and is less liable to choke or clog.

Having thus described my invention, what I claim as new, and desire to secure by Letters Patent, is—

The combination of the spheroidal cutter, C, and the fluted cylinders, E E, arranged to

operate substantially as and for the purpose set forth.

R. M. CURTICE.
